US00D712414S

(12) **United States Design Patent**
Tsai et al.

(10) **Patent No.:** US D712,414 S
(45) **Date of Patent:** ** Sep. 2, 2014

(54) **FLASH DRIVE**

(71) Applicant: **Power Quotient International Co., Ltd.**, New Taipei (TW)

(72) Inventors: **Chia-Hsin Tsai**, New Taipei (TW); **Hung-Yi Lin**, New Taipei (TW); **Yu-Cheng Chang**, New Taipei (TW); **Ya-Fen Chen**, New Taipei (TW)

(73) Assignee: **Power Quotient International Co., Ltd.**, New Taipei (TW)

(**) Term: **14 Years**

(21) Appl. No.: **29/466,633**

(22) Filed: **Sep. 10, 2013**

(51) LOC (10) Cl. **14-02**

(52) U.S. Cl.

USPC **D14/480.6**

(58) **Field of Classification Search**

CPC H05K 5/0278; H05K 7/1454; G06K 19/07732; G06K 19/07741

USPC D14/411, 433, 435.1, 436, 480.1–480.7, D14/484.1, 137, 155, 203.1–203.8, 240, D14/242; D13/133, 146–147, 154, 184; 439/79, 607.23, 607.34, 638, 640, 660

(57) **CLAIM**

The ornamental design for a flash drive, as shown and described.

DESCRIPTION

FIG. 1 is a perspective view of a flash drive showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view showing the flash drive in use.

The broken line showing is for the purpose of illustrating portions of the flash drive and forms no part of the claimed design.

1 Claim, 8 Drawing Sheets
